UNITED STATES PATENT OFFICE.

JOHN T. SIMONS, HENRY D. ELLIOTT, AND THOMAS P. STONEY, OF CHARLESTON,
SOUTH CAROLINA.

AUTOMOBILE STORM CURTAIN.

Application filed July 11, 1922. Serial No. 574,142.

To all whom it may concern:

Be it known that we, JOHN T. SIMONS, HENRY D. ELLIOTT, and THOMAS P. STONEY, citizens of the United States, and residents ⁵ of Charleston, in the county of Charleston and State of South Carolina, have invented certain new and useful Improvements in Automobile Storm Curtains, of which the following is a specification.

10 This invention relates particularly to side curtains for automobiles and an object thereof is to provide such curtains that can be quickly attached to the frame of the automobile or detached therefrom, and which can 15 be readily and easily moved to an inoperative position when not in use.

Another object of the invention is to provide means for carrying a plurality of curtains so that the curtains may be used ²⁰ 20 separately or together as desired.

Another object is to so arrange the carrying frame that the curtains when not in use are carried in a longitudinal position by the side bar of the top frame.

25 Other objects will be apparent from the following detailed description and appended claims.

In the drawings:

Figure 1 is a side elevation of a part of ³⁰ 20 an automobile with the curtains in their operative position.

Figure 2 is a side view on an enlarged scale of the attachment and curtains in operative position.

35 Figure 3 is a top plan view, partly in section taken on the line 3—3 of Figure 2.

Figure 4 is a vertical section of the device with the curtain carrying frame in operative position.

40 A part of the frame A of an automobile is shown, having a top B carried in the usual manner and attached at its sides to side bars C. Fastened to the side bar C is a pair of headed screws, bolts, pins or ⁴⁵ 45 similar members 1 which are designed to support the attachment. A metal bar or strip 2 having its central portion offset outwardly as shown in Figure 3, is provided with a pair of key hole slots 3, by which the bar 2 may be quickly placed upon the members 1 and as quickly removed therefrom. The upper portion of the key hole slots 3 will be too small to permit the passage of the heads of the members 1, so that ⁵⁰ 50 there is no danger of accidental displace-

ment, but the whole device can be removed at any time by simply lifting the same slightly and then moving it outwardly.

The bar 3 may have an enlarged central portion 4 through which passes a bolt 5. ⁶⁰ The metal frame which supports each curtain roller has an ear 6 which is substantially co-extensive with the enlarged portion 4 of the bar, and the bolt 5 passes through these ears and thus attaches the curtain roller frames to the bar 3. Each ear fits over the bolt 5 loosely enough to allow the frame to be turned on the bolt as a pivot. ⁶⁵

The two curtain roller frames 7 and 8 ⁷⁰ are identical in most features, and as shown in Figure 4, each consists of a vertical portion 10, top and bottom portions 11 and 12, each of which has its ends turned toward each other to lie substantially parallel ⁷⁵ with the portion 10, and the ear 6. Each frame may be made of sheet metal which facilitates its production.

The upturned end 13 of the bottom 12 is provided with a slot 14 which cooperates ⁸⁰ with a button 15 carried by the side of the car to fasten the frame in operative position. This form of fastening device is merely illustrative, as any other equivalent form may be employed without departing ⁸⁵ from the spirit of the invention. Similar buttons 16 will be placed on the top to cooperate with the slots 14 to hold the curtain frames in their inoperative position. ⁹⁰

At its inner edge one of the frames, here ⁹⁵ shown as the frame 8, has a shoulder formed as indicated at 17 in Figure 2 which will lap over the outside of the meeting edge of the frame 7. This will act as a weather strip and tend to prevent dirt or moisture passing between the meeting edges of the two strips. If desired this overlapping portion might be made in a separate strip and attached to one of the frames, but it is preferable to make it integral with one frame as shown. ¹⁰⁰

Each frame has a roller 9 mounted therein on pintles 18 and 19. This is a spring roller of the usual or any desired type upon which the curtain may be wound when not in use. The curtains are of the usual type and have ¹⁰⁵ button holes that cooperate with the usual fastening buttons on the automobile as indicated at 20 when the curtains are unrolled for use.

Assuming the curtains to be in operative ¹¹⁰

position as in Figure 1, if it is desired to put them up, the fastenings 20 are released and the curtains rolled up on the rollers 9. The buttons 15 are turned to release the frames 5 7 and 8, and these frames are swung about the pivot 5, one towards the front and the other towards the rear as indicated by the dot and dash lines in Figure 1, to a position where the fastenings 16 may engage the 10 holes 14 and secure the frames in position so that they lie along the under side of the top longitudinally of the machine.

If it should be desired to remove the attachment entirely, the curtains are rolled 15 and the fastenings 15 released, whereupon the whole attachment may be lifted slightly and taken off, the heads of the members 1 passing freely through the lower enlarged portions of the slots 3.

20 If so desired, either curtain may be used independently of the other, the one not in use remaining in its folded position along the top. The exact place of attachment and specific form of curtains will vary with the 25 type of machine to which the device is applied. Various changes may be made in size and proportions without departing from the spirit of the invention, which is to be regarded as limited only by the scope of the 30 appended claims.

We claim as our invention:

1. A storm curtain attachment for automobiles, comprising a member carried by the automobile top, frames pivoted to said 35 member and independently movable in opposite directions about a single pivot, means for holding the frames in raised or lowered position, a roller carried by each frame and a curtain on each roller.
- 40 2. A storm curtain attachment for automobiles, comprising a member having slots therein to detachably engage devices carried by the side bar of an automobile top, frames pivoted to said member and independently movable in opposite directions 45

about a single pivot, means for holding the frames in an operative position extending longitudinally of the top, means for holding the frames in operative position, a roller carried by each frame, and a curtain on each 50 roller.

3. A storm curtain attachment for automobiles, comprising a member having means for quick detachable engagement with the side bar of an automobile top and having an 55 enlarged porton, a plurality of frames, an ear on each frame, a single pivot bolt engaging the ears and said enlarged portion and permitting the frames to be swung in opposite directions independently and longitudinally of the automobile, and a curtain carried by each frame.

4. A storm curtain attachment for automobiles, comprising a plurality of frames, a 60 spring roller carried by each frame, a curtain carried by each roller, means for supporting the frames to turn about a common pivot in opposite directions, means for supporting said pivot from the top of an automobile, and means for holding the frames 70 in operative or inoperative position.

5. A storm curtain attachment for automobiles, comprising an attaching device carried by the automobile top, a support having quick detachable engagement with said device, a plurality of frames carried by said support, a curtain roller carried by each frame, each frame mounted on the support to move independently to an inoperative position extending longitudinally of the machine or to a substantially vertical operative position, and means for maintaining the frames separately in either position as desired.

In testimony whereof, we have hereunto 85 subscribed our names.

JOHN T. SIMONS.
HENRY D. ELLIOTT.
THOMAS P. STONEY.
